UNITED STATES PATENT OFFICE.

WILLIAM A. PRESTON AND GEORGE M. DUFFIE, OF DETROIT, MICHIGAN.

CENTRIFUGAL SEPARATOR.

No. 918,592.

Specification of Letters Patent.

Patented April 20, 1909.

Application filed October 5, 1907. Serial No. 896,050.

To all whom it may concern:

Be it known that we, WILLIAM A. PRESTON and GEORGE M. DUFFIE, citizens of the United States of America, residing at Detroit, in the county of Wayne and State of Michigan, have invented certain new and useful Improvements in Centrifugal Separators, of which the following is a specification, reference being had therein to the accompanying drawings.

The invention relates to centrifugal separators, and has more particular reference to the means employed for mounting and driving the bowl.

It is the object of the invention to obtain an automatically balancing mechanism for the bowl and, further, to lessen the effort necessary in overcoming the inertia of the bowl when the machine is started.

With these objects in view, the invention consists in the novel construction as herein-after set forth.

In the drawings—Figure 1 is a vertical central section through a portion of the bowl and its drive mechanism; Fig. 2 is a similar view illustrating a modification; and Fig. 3 is a diagrammatic view of the complete machine.

In the operation of centrifugal separators, which are driven at high angular velocity, it is essential that the revolving part should be accurately balanced to bring the center of the mass as near as possible into alignment with the axis of the spindle. The operation of balancing is a delicate and difficult one and at best is only approximately correct. We have therefore provided a construction in which the balancing of the bowl is accomplished automatically and which, when once in balance, is locked to retain this adjustment during the continued rotation of the bowl. Where centrifugal separators are hand driven the required velocity can only be obtained by a step-up gearing, which requires, for the overcoming of the inertia of the bowl in starting, a considerable effort on the part of the operator. When, however, the required velocity is attained it may be maintained with comparatively little effort. It is a further object of our invention to avoid the fatigue due to the starting of the bowl by providing means for gradually accelerating the rotation thereof, while the

drive mechanism is actuated at a uniform speed. To this end we have provided a friction drive operative when the machine is first started, together with means for positively coupling the drive mechanism to the bowl when full velocity is attained.

With the construction as shown, A is the bowl and B the driving spindle therefor. The bowl is connected with the spindle by a universal coupling C such, for instance as a ball and socket joint, the arrangement being such as to permit of independent rotation of the spindle. In addition to this coupling there is provided a supporting bearing D for the bowl, which limits the adjustment of the universal coupling and holds the bowl in a substantial vertical position. Thus, in the starting of the machine, the bowl, which is only frictionally driven through the medium of the universal coupling, is permitted to lag behind, the rotation of the spindle being gradually accelerated until full velocity is attained. During this acceleration, the bowl will gradually assume a position where it rotates about its true center of mass, the universal joint permitting of this adjustment, and as a consequence the bowl is automatically balanced. As soon as the bowl is brought into balance, and is driven at the required velocity, it is desirable to positively couple it to the driving spindle. This, as shown, is accomplished by an automatic mechanism comprising weighted arms E carried by the revolving mechanism, and which are thrown out by centrifugal action, to operate the positively coupling clutch. We positively arrange the arms E upon the spindle, to which they may be attached by suitable means, such as the collar F, having pivot bearings G for the arms. The clutching is preferably accomplished by drawing downward the bowl after it has been brought into balance until it rests upon the member D and is frictionally locked thereto in said balanced position and kept there frictionally against any further effort on the part of the weighted arms E. To this end, the ball H of the coupling C is secured to a shank I telescopically engaging a tubular portion J of the spindle and supported at its lower end upon a spring K. At the lower end of this shank are formed bearings L with inwardly projecting fingers M on the

weighted arms E engage, said fingers passing through slots N in the tube J. The construction just described is such that normally the shank I is pressed upward by the 5 spring K, so as to hold the bowl out of engagement with the member D, but as soon as the weights E are thrown outward by centrifugal action, the fingers M will draw downward the spindle until the bowl is 10 brought into contact with the member D.

In the construction as illustrated in Fig. 1 the member D extends across the entire bottom of the bowl, and has a concave bearing O near its periphery for engaging a convex bearing P on the bowl. These surfaces O and P are thus engageable with each other in different positions of angular adjustment of the axis of the bowl, which permits said bowl to find its true center of rotation and 15 then to be coupled to the member D in this position of adjustment. In the construction illustrated in Fig. 2, the member D' is of lesser diameter and is of substantially spherical form, having a concave surface Q 20 which is substantially concentric with the ball H. The ball is secured in a socket upon the bowl, having a cap member R which has a convex outer surface S also concentric with the ball. Thus whatever adjustment is given 25 to the bowl in relation to the spindle, the surface S will always be engageable with the surface Q.

With the construction as described in operation the bowl is driven through the 30 medium of suitable drive mechanism comprising an actuating crank T and suitable gearing U intermediate the crank and the spindle B. During the initial movement, the bowl, being merely supported by resting 35 upon the ball H, will permit the spindle to rotate at a higher velocity, but the frictional engagement between the ball and its socket will constantly accelerate the bowl. At the same time, the rotation of the spindle will 40 throw into operation the centrifugal arms E, which will draw downward the shank I until a positive coupling is effected between the bowl and the spindle. Thus the two-fold object is accomplished, first, of automatically bringing the bowl into balance, 45 and secondly, of limiting the effort necessary to start the machine.

What we claim as our invention is:

1. In a centrifugal separator, the combination with a revoluble bowl, of an independently revoluble spindle supporting the same and universally pivoted thereto, and automatic means for locking said bowl and spindle when revolving at a predetermined 50 speed to cause them to rotate together.

2. In a centrifugal separator, the combination with a revoluble bowl and an independently revoluble spindle having a fric-

tional engagement therewith, of centrifugal means for automatically locking said bowl 65 and spindle to rotate together when a predetermined velocity is acquired.

3. In a centrifugal separator, the combination with a revoluble spindle, of a bowl coupled to said spindle by a universal joint, 70 which joint permits said bowl to find its true axis of rotation, and means operating automatically upon the acquirement of a predetermined velocity for effecting a rigid coupling between said bowl and said spindle. 75

4. In a centrifugal separator, the combination of a bowl and a vertical spindle to which said bowl is connected, said connection permitting the bowl to find its true axis of rotation, of a drive mechanism for said 80 spindle including a step-up gear train, a slip coupling between said spindle and bowl permitting the latter to lag in the starting of the machine, and means for locking said coupling when predetermined velocity is 85 acquired.

5. In a centrifugal separator, the combination of a bowl and a vertical spindle on which said bowl is mounted, a ball and socket coupling between said bowl and 90 spindle permitting of independent rotation and angular adjustment, a bearing upon said spindle beneath said coupling, a co-operating bearing on the bowl, and means for drawing said co-operating bearing into 95 contact to lock the spindle to the bowl.

6. The combination with a revoluble spindle, of a member coupled to said spindle by a universal joint, which joint permits said member to find its true axis of rotation, and 100 means operating automatically upon the acquirement of a predetermined velocity for effecting a rigid coupling between said member and spindle.

7. The combination with a revoluble member 105 and a vertical spindle upon which said member is mounted, a ball and socket coupling between said member and spindle permitting of independent rotation and angular adjustment, a bearing upon said 110 spindle beneath said coupling, a co-operating bearing upon said revoluble member and means for drawing said co-operating bearing into contact to lock the spindle and revoluble member. 115

8. In a centrifugal separator, the combination of a bowl, a drive spindle therefor, a shank telescopically engaging said spindle and having a universal coupling with said bowl, a bearing fixed upon said spindle beneath said bowl and means for drawing downward said shank to engage the bowl with said fixed bearing upon the spindle. 120

9. In a centrifugal separator, the combination with a bowl, of a vertical spindle 125 having a tubular upper end and an enlarged

bearing for the bowl thereon, a shank tele-
scopically engaging the tubular portion of
said spindle, a ball and socket coupling be-
tween said shank and bowl, a spring for
raising said shank to hold the bowl out of
contact with said enlarged bearing and cen-
trifugal means for drawing downward said
shank to rest the bowl on said bearing.

In testimony whereof we affix our signa-
tures in presence of two witnesses.
